(57) **CLAIM**

The ornamental design for a combined advertising machine with magazine rack, as shown and described.

DESCRIPTION

FIG. 1 is a perspective view of a combined advertising machine with magazine rack showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line portion of the figure drawings is included to show portions of the combined advertising machine with magazine rack that forms no part of the claimed design.

1 Claim, 7 Drawing Sheets
